Primary Examiner — Garth Rademaker*Assistant Examiner* — Laura H Yu(74) *Attorney, Agent, or Firm* — Olive Law Group, PLLC(57) **CLAIM**

The ornamental design for a punching cradle, as shown and described.

DESCRIPTION

FIG. 1 is a top, front and right side perspective view of a punching cradle, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 2.

The evenly broken lines illustrate the features of the punching cradle that form no part of the claimed design. The unevenly broken lines illustrate the boundaries of the enlarged view that form no part of the claimed design.

1 Claim, 9 Drawing Sheets(56)
